UNITED STATES PATENT OFFICE.

MARTIN A. KALTON, OF MINNEAPOLIS, MINNESOTA.

DOOR-SPRING.

1,354,196.

Specification of Letters Patent. Patented Sept. 28, 1920.

Application filed June 7, 1920. Serial No. 387,265.

To all whom it may concern:

Be it known that I, MARTIN A. KALTON, a citizen of the United States, residing at Minneapolis, in the county of Hennepin and

5 State of Minnesota, have invented a new and useful Door-Spring, of which the following is a specification.

The device forming the subject matter of this application is adapted to be used in connection with doors which are in almost continuous use, spring means being provided for closing the doors.

It is a well known fact that under continued use, the door spring lasts but a short time, and one object of the invention, therefore, is to provide a spring-closing means for a door, which will withstand severe usage to which devices of this kind are subjected commonly.

20 The invention aims to provide novel means whereby a spring may be supported and protected, novel means being supplied for putting the spring under compression, and novel means being included whereby the 25 device may be adjusted to coöperate with the door which is to be closed.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention 35 shown can be made without departing from the spirit of the invention.

In the accompanying drawings:

Figure 1 shows in elevation, a portion of a door frame and a door, whereunto the structure forming the subject matter of this application has been applied; Fig. 2 is a section on the line 2—2 of Fig. 1; and Fig. 3 is a section on the line 3—3 of Fig. 2.

In the drawings, there appears a door frame comprising a jamb 1 and a lintel 5. A door appears at 2 and is hinged at 3 to the jamb 1, the door being supplied on its sides, and at its upper edge, with wear strips 4.

The invention embodies a bracket, denoted generally by the numeral 6, the bracket embodying a base 7, a top plate 8 which is approximately semi-circular, and a bottom flange 9, the flange 9 terminating short of one end of the base 7, for a purpose to be described hereinafter.

The numeral 10 denotes an arm including a base 11, triangular sides 12 and an end 14, this particular shape serving to give the arm great strength. The arm extends between the flange 9 and the top plate 8 of the bracket 6, the sides 12 of the arm being connected to the flange and the top plate by a pivot element 15. The base 11 of the arm 10 is provided with a depending lip 18 and it is 60 the purpose of accommodating this lip that the flange 9 of the bracket 6 terminates short of one end of the bracket, as aforesaid. An adjustable abutment, such as a screw 19, is located in the lip 18 and is held therein by 65 nuts 20. The abutment 19 is adapted to be engaged by one of the wear strips 4 on the door 2, and it will be clear that by shifting the nuts 20 on the screw 19, the position of the screw with respect to the door may be 70 altered, thereby adapting the device to varying conditions.

The numeral 16 denotes an arcuate support, having its ends extended through the base 7 of the bracket 6. One end of the support 16 engages the inner surface of the base 7, as indicated at 22. A securing element 23 extends through the top plate 8 of the bracket 6 and through the flange 9 thereof, the securing element passing 80 through the arcuate support 16. That end of the arcuate support 16 which is adjacent to the securing element 23, may be extended, as shown at 24, through the base 7, into the jamb 1, to aid in anchoring the bracket in 85 place. The base 7 of the bracket 6 is provided, as shown in Fig. 3, with an opening 30, through which the end 22 of the support 16 extends, the base 11 of the arm 10 having an opening 31 which receives the support 16, the arm thus being slidably mounted 90 on the support. A helical compression spring surrounds the support 6, the spring being denoted by the numeral 21. One end of the spring abuts a securing element 23, and the other end of the spring abuts 95 against the base 11 of the arm 10. When the door is swung on the hinge 3, the door bears against the abutment 19, and the arm 12 is swung on the pivot element 15, the 100 spring 21 being put under compression. Obviously, the spring 21 reacts on the arm 12 to move the door to a closed position. It is to be observed that the top plate 8 of the bracket is of sufficient size to extend above 105 and to shield both the arcuate support and the spring 21 which is mounted thereon.

Having thus described the invention, what is claimed is:—

1. In a device of the class described, a door frame; a hinged door; a bracket carried by the frame; an arm pivoted to the bracket and having a depending lip; an arcuate support connected at its ends to the bracket, the arm being slidable on the support; a compression spring on the support and abutting at one end against the arm; a stop adjustable in the lip and located in the path of the door; and means for holding the top in adjusted positions in the lip.
2. In a device of the class described, a door frame; a hinged door; a bracket carried by the frame; an arcuate support connected at its ends to the bracket, the bracket including a top plate of sufficient size to shield the support, and a bottom flange below the support; an arm extended between the top plate and the flange and slidable on the support; a pivot element mounted in the top plate and in the flange and constituting a mounting for the arm; a spring on the support and abutting against the arm; an

adjustable stop on the arm and lying in the path of the door; and means for holding the stop in adjusted positions on the arm.

3. In a device of the class described, a door frame; a hinged door; a bracket carried by the frame; an arcuate support connected at its ends to the bracket, the bracket including a top plate of sufficient size to shield the support, and a bottom flange below the support; an arm including a base, an end, approximately triangular walls connecting the base and the end, the arm being located between the top plate and the flange; a pivot element connecting the top plate and the flange with the sides of the arm; and a lip projecting from the base of the arm, the lip lying in the path of the door.

In testimony that I claim the foregoing as my own, I have hereto affixed my signature in the presence of two witnesses.

MARTIN A. KALTON.
